RAILWAY AMUSEMENT APPARATUS

John F. Courtney, Florence, S. C., assignor of
one-half to Heyward S. Dennis, Augusta, Ga.

Application December 22, 1937, Serial No. 181,231

11 Claims. (Cl. 104—76)

My invention relates to a railway amusement apparatus.

An important object of the invention is to provide apparatus of the above mentioned character which will be attractive to riders and will produce thrills, and yet will be safe.

A further object of the invention is to provide apparatus of the above mentioned character, which will carry the passenger through a loop travel, and invert the passenger through a portion of the travel.

A further object of the invention is to provide means which may be operated to partly invert the passenger while approaching the inverted position but will restore the passenger to the upright position before reaching the completely inverted position.

A further object of the invention is to provide means for effecting the travel of the passenger, or any number of passengers, while pivotally supporting them, permitting of the inverting of the passenger during a portion of the travel, and restoring the passenger to the upright position when desired, which may be done automatically or at the will of the operator.

A further object of the invention is to provide means for causing the vehicle or cars to travel properly around the curved portions of the track, without liability of moving from the track, and without binding when travelling over the curved portions.

A further object of the invention is to provide a train to travel upon the track which will possess the desired flexibility so that the proper travel of the train will be obtained.

A further object of the invention is to provide an arrangement of the current transmitting means which is in convenient reach of the motor propelling the vehicle or train, but is entirely out of the reach of the passengers of the train and bystanders.

A further object of the invention is to provide apparatus of the above mentioned character which is relatively simple, strong and extremely safe in operation.

Other objects and advantages of the invention will be apparent during the course of the following description.

In the accompanying drawings forming a part of this application and in which like numerals are employed to designate like parts throughout the same,

Figure 1 is a side elevation of apparatus embodying my invention,

Figure 2 is a plan view of the same,

Figure 3 is a transverse section taken on line 3—3 of Figure 1,

Figure 3a is a section taken on line 3a—3a of Figure 1,

Figure 4 is a longitudinal section taken on line 4—4 of Figure 3,

Figure 5 is a plan view of one of the cars,

Figure 6 is a central vertical longitudinal section through one of the cars, the same being inverted, and the passenger supporting element 10 locked in the inverted position,

Figure 7 is a diagrammatic view showing the circuits,

Figure 8 is a diagrammatic view of the continuous trip contacts,

Figure 9 is a diagrammatic view similar to Figure 7, but showing modified forms of trip contacts, and,

Figure 10 is a plan view of the trip contacts, the circuits being shown diagrammatically.

In the drawings, wherein for the purpose of illustration are shown preferred embodiments of my invention, the numeral 15 designates a vertical supporting structure or frame, as a whole, which is formed in separable units so that it may be readily assembled and separated. The frame comprises a plurality of vertical supporting units 16. Each vertical supporting unit comprises a pair of vertical uprights or posts 17, connected at their upper ends by a horizontal beam 18, detachably secured to the posts 17 by bolts 19 or the like, engaging lateral extensions 20 of the posts 17. At their lower ends, the posts 17 have lateral extensions 21, detachably secured to a lower horizontal beam 22, by bolts 23 or the like.

Arranged upon the outer sides of the posts 17 are diagonal braces 24, the upper ends of which are detachably connected with the posts 17 by bolts 25 or the like, while their lower ends have lateral extensions 26, detachably secured to the lower beam 22 by bolts 27 or the like. The several lower beams 22 are arranged upon suitable foundations, so that the supporting frame will have its several units arranged in alignment and held in such alignment. The pairs of end posts 17 have detachable connection with longitudinally extending diagonal braces 28, the lower ends of which are detachably connected with horizontal beams 29, in turn detachably connected with the lower horizontal beams 22 of 50 the end units 16. The outer ends of the beams 29 are detachably connected by a transverse horizontal beam 29'. It is preferred to reinforce and stiffen the supporting frame or structure, particularly during its erection, since it is assembled 55

from one end to the other, and to accomplish this, diagonal braces 30 are provided, which cross, and are detachably connected at their ends with the posts 17 of the adjacent pair of supporting units 16, next to the opposite ends of the supporting frame. The lower ends of the vertical posts 17 in the pairs of units 16 connected by the diagonal braces 30 may also be detachably connected by horizontal beams 31.

10 An elongated plate 32 is arranged beneath and secured to the upper horizontal beam 18, by bolts 33 or the like. This plate may be integral with the beam 18, which would then be a T-beam. The plate 32 projects beyond the opposite sides 15 of the beam 18, for attachment purposes. In a similar manner, an elongated plate 34 is rigidly secured to the lower horizontal beam 22, by bolts 35 or the like, and the plate 34 may be integral with the beam 22, if desired, the beam 22 then 20 being in the nature of a T-beam. At their upper ends, the vertical supporting units 16 are all detachably connected by strips or beams 36, sufficiently rigid, which are detachably connected to the posts 17 by bolts 37 or any other suitable 25 means, the adjacent ends of the strips 36 overlapping, as shown.

Extending longitudinally within the supporting frame or structure 15 is an elongated or generally elliptical track 38, comprising a spaced pair 30 of generally elliptical rails 39. The rails 39 are preferably formed of I-beams, Figure 3a, affording inner and outer flanges 40 and 41, although these rails may be channel irons. The tracks 38 comprise upper and lower runs 42 and 43 and curved ends 44, vertically arranged for connecting the upper and lower runs. It is preferred to have the length of the runs considerably longer than the length of the curved ends 44, so that the car or train may gain suitable velocity before engaging the curved ends and to also provide a ride of suitable length. However, the length of the runs may be varied as found advantageous, by removing or inserting rail sections. In the upper and lower runs 42 and 43, the rails 39 are formed in sections 39a, preferably having a length for spanning the distance between three of the vertical supporting units 16, but of course the invention is not restricted to this feature, as they may span only two of the supporting units 16 or more than three, as desired. The outer flanges 41 of the rails 39 are bolted at their ends, and at their centers with the plates 32 and 34, as shown at 45 and 46, as shown more clearly in Figure 3. The curved rail ends 44 are bolted to the plates 32 and 34 as shown at 48, Figure 4, and are also bolted, between their ends at 49 with plates or beams 50, detachably rigidly secured to the posts 17 of the end supporting units. Arranged between the rails 50 39 is a generally elliptical rack 51, corresponding in shape and dimensions to the generally elliptical rails. This rack has its teeth 52 facing inwardly and the rack includes upper and lower runs 42' and 43' corresponding to the track runs 42 and 43 and curved ends 44' corresponding to the track ends 44. The upper and lower runs 42' and 43' are made in sections or lengths corresponding to the rail sections 39a and are designated 39b, and are detachably secured to the plates 32 and 34 by bolts 53 and 54. The ends 44' are detachably secured to the plates 32 and 34 by bolts 55' or the like, corresponding to the bolts 48, and the ends 44' are also detachably secured to the strips or beams 50 by bolts 49a 75 corresponding to the bolts 49.

In Figures 7 and 8, I have shown pairs of trip-contact rails 55 and 56, which are generally elliptical and correspond to the shape and dimensions of the track rails 39, and made in sections corresponding to the lengths of rail sections. The 5 pairs of trip-contact rails 55 and 56 are detachably connected with the plates 32 and 34 and insulated therefrom. Wires 57 and 58 are connected with the opposite poles of the source of current and a wire 59 is connected with the wire 10 57 and with one trip-contact 55 while a wire 60 is connected with the wire 58 and is also connected with the other trip-contact 55. The wire 59 has a switch 61 connected therein. It is thus seen that when the switch 61 is closed the trip-contacts 55 will be connected with the opposite poles of the source of current. A branch wire 62 is connected with the wire 57 and is connected with one trip-contact 56 and has a switch 63 connected therein. The other trip-contact 56 is 20 connected with a wire 64, connected with the wire 58. When the switch 63 is closed, the trip-contacts 56 will be connected with the opposite pole of the source of current. The pairs of trip-contacts 55 and 56 are continuous and extend 25 throughout the entire length of the track, for a purpose to be explained.

In Figures 9 and 10, I have shown two pairs of trip-contacts 65 and 66, which are relatively short, and arranged near the ends 44 of the track 30 and located at the upper run. These trip-contacts preferably have a length corresponding to the distance between two of the supporting units 16 and are detachably connected with the plates 32 and are insulated therefrom. Wires 67 and 35 68 are connected with the opposite pole of the source of current, and the wire 67 is connected with one trip-contact 65 in each longitudinal pair by a wire 67' and has a switch 69 connected therein. A wire 70 is connected with the other trip-contact 65 in each longitudinal pair and with the wire 68. A branch wire 71 is connected with the wire 67 and has a switch 72 connected therein and is connected with the trip-contact 66 in each longitudinal pair of trip contacts. A branch wire 73 is connected with the wire 68 and with the remaining trip-contact 66 in each longitudinal pair of trip-contacts. It is thus seen that means are provided for independently connecting the pairs of trip-contacts in each pair with 45 the source of current. 50

The numeral 74 designates a pair of power rails, which are generally elliptical, and arranged within the generally elliptical tracks and supporting frame. These power rails are mounted upon and insulated from transverse beams 75, 55 detachably mounted upon each of the supporting units 16. The power rails 74 are formed in sections, preferably corresponding to the length of the rail sections in the upper and lower runs 60 42 and 43. The ends 76 of the power rails are curved and concentric with the track ends 44. It is preferred to use two of the power rails 74, but of course the invention is not restricted to this procedure as the source of power may be 65 grounded to the track rails and one power rail used.

I will now describe the vehicle to travel upon the track. In the example given, I have illustrated a train comprising an engine and a plurality of cars. Each passenger car comprises a rectangular frame 77, see more particularly Figures 4, 3a, 5 and 6. The frame 77 travels between the rails 39. Disposed outwardly of and near each side 78 of the frame 77 are vertically 75

swinging arms or levers 79, Figure 3a, extending above and below the side 78, and these arms or levers are pivotally mounted, between their ends, upon trunnions 80, clamped within sleeves 81, formed upon the side 78. Vertical wheels 82 and 83 are rotatably mounted upon spindles 84, carried by each arm 79, and the vertical wheels 82 and 83 travel above and below the outer flange 40, to engage therewith. Horizontal wheels 85 are rotatably mounted upon brackets 86, rigidly secured to the ends of the frame 77 and contact with the outer flange 40, preventing lateral displacement of the car. It is thus seen that each car will travel upon the rails 39, and will be held thereon when travelling upon the lower run, and also when inverted and travelling upon the upper run. The pivoted arms or levers 79, being capable of swinging upon the trunnions 80, will automatically adjust themselves when the carriage is travelling upon the curved ends 44, preventing binding action between the wheels and the curved track ends. Each car frame 77 is provided with a pair of vertical upstanding posts 87, considered before the car frame is inverted. The inner ends 25 of the posts 87 are rigidly secured to the frame 77 while their outer ends are connected by a transverse shaft 88, passing through openings 89 formed upon a U-shaped hanger or yoke 90, there being pivotally mounted upon the shaft 88. The U-shaped hanger has a transverse inner portion 91. The numeral 92 designates a passenger supporting element, preferably in the form of a seat, which is rigidly attached to the U-shaped hanger 90, to move therewith. This seat is preferably provided with an enclosure 93, formed of wire mesh of suitable strength or gage, having a suitable door (not shown) for the entrance and exit of the passenger. The seat may be equipped with a strap 94 and a hand bar 95 of any well known or preferred type for properly retaining the passenger upon the seat, particularly when he is travelling inverted.

It is intended that the passenger be inverted while travelling upon the upper run 42 throughout the entire length of the upper run, or a part thereof, and in order that this may occur, the car does not turn for a complete revolution with respect to the passenger supporting element but only for about one-half of a revolution with respect thereto, or otherwise the passenger supporting element would remain upright and the passenger would not be inverted. The inverting of the passenger is one of the important features of the invention as it produces a thrill. It is therefore necessary to provide means for locking the passenger supporting element to the car so that the car cannot turn with relation to the passenger supporting element, during a portion of the inverting movement or revolution of the car. To accomplish this, I provide each car with a vertically movable rear bolt 96, Figures 4 and 6, to engage behind the transverse portion 91 of the U-shaped hanger and projected outwardly by a compressible coil spring 97. This bolt has a bevelled rear face 98. The bolt 96 is retracted to release the transverse portion 91 by a solenoid winding 99. The opposite ends of this solenoid winding are electrically connected with resilient contacts 100, arranged to engage with the trip-contacts 56. A similar bolt 101 is arranged in advance of the transverse end 91 of the hanger and is projected forwardly by a compressible coil spring 102 and is retracted by a solenoid winding 103, the opposite ends of which are electrically connected with resilient contacts 104, to engage

with the trip-contacts 55. In connection with the trip-contacts 55 and 56 which are continuous throughout the length of the tracks, either solenoid winding 99 and 103 may be energized while the car is travelling throughout the entire length 5 of the trip-contacts 55. When the cars are used with the pairs of trip-contacts 65 and 66, the resilient contacts 100 may engage the contacts 66, and the resilient contacts 104 engage the contacts 65. 10

The several cars are propelled by means of an engine 105, including a frame 106, equipped with vertical wheels 107, corresponding to the wheels 82 and 83 and mounted upon the frame 106 in the same manner as described in connection with each 15 carriage. The frame 106 carries a transverse shaft 108, suitably journaled thereon, and this shaft has a gear 109, in permanent mesh with the teeth 52 of the rack. The gear 109 is preferably integral with a larger gear 110, engaging and 20 driven by a smaller gear 111, rigidly mounted upon an upper transverse shaft 112, suitably journaled in the frame 106. The upper shaft 112 has a relatively large bevel gear 113 rigidly mounted thereon, engaged and driven by a smaller bevel 25 gear 114, in turn driven by an electric motor 115, although any other suitable form of prime mover may be used. The opposite poles of the motor have electrical connection with resilient contacts 116, arranged to engage with the power rails 74. 30 One power rail is electrically connected with the wire 57 while the other power rail is electrically connected with the wire 58, having a rheostat 58' connected therein. In order that the train embodying the cars and engine may possess suitable 35 flexibility for travelling over the curved ends 44, the several cars are pivotally connected by rigid tongues 117, which are pivotally connected with U-shaped sockets 118, rigidly attached to the frames 77, by bolts 119. In a similar manner, a 40 rigid tongue 120 is pivotally connected with a socket 121 carried by the frame 106. 45

The track 38 is disposed in a vertical plane, and the posts or supports 87 secured to the cars extend inwardly from the cars and are arranged 45 within the track. The passenger supporting elements 92 being pivotally mounted upon the inner ends of the posts or supports 87 are also arranged within the track, and the passenger supporting elements travel at a lower speed around the curved ends of the track than the cars, since the elements are arranged nearer the center of the curve. By arranging the supports and passenger supporting elements within the track, the lower run of the track may be arranged adjacent to the 50 loading surface. 55

The operation of the apparatus is as follows: The engine propels the train of cars to the left, Figures 1, 2, and 4. The latches 96 and 101 being now both projected, the passenger supporting element 92 is locked to the car frame 77, and both the car frame and the passenger supporting element travel upwardly upon and over the left end 44 and both turn together for one-half of a complete revolution. If the solenoid windings 99 and 103 are not energized, which may be accomplished if desired, the passenger carrying element will remain locked to the carriage frame 77 and hence the passenger carrying element will be inverted throughout the entire travel of 70 the carriage upon the upper run 42. I contemplate operating the apparatus in this manner for it would produce the maximum thrill. However, after the passenger supporting element has made a half revolution with the carriage frame 77 and 75

has become inverted, I contemplate releasing the passenger supporting element so that it may drop forwardly after being inverted, at any given point along the upper run and hence will immediately swing or gravitate to the upright position. This is accomplished by connecting the trip contacts 55, the first form of the invention being now considered as shown in Figures 7 and 8, with the source of current whereby a circuit 5 will be closed and the solenoid winding 103 energized, retracting the forward bolt 101. The passenger supporting element or seat 92 will now swing or drop forwardly with respect to the frame 11. This action will occur because the center of gravity of the load carried by the element 92 is well forwardly of the pivot 88. When the hanger 87 reaches the vertical upright position, it will pass over the bevel face 98 of the rear bolt 97 and hence the bolt will again engage behind the transverse portion of the hanger, when the frame 78 of the carriage travels downwardly for one-half of a revolution about the right end 44 of the track while the hanger 87 remains upright. In this operation, it is seen that 15 the carriage 11 only travels for one-half of a revolution with respect to the passenger supporting element 92. If the front bolt 101 were not employed, the passenger supporting element 92 would automatically drop to the upright position 20 as soon as it is inverted, that is shortly after passing from the left end 44 of the track. I contemplate dispensing with the front bolt 101 and using the rear bolt 96, with or without the solenoid winding to retract the rear bolt. It is 25 preferred to use the front bolt 101 as it will hold the passenger supporting element against forward downward swinging movement and will permit of the releasing of the passenger supporting element at various points along the upper run. A further advantage in using the front 30 bolts 101 in combination with the continuous trip-contacts 55 is that all of the passenger supporting elements 92 may be allowed to travel, inverted, upon the upper run 42 and then dropped simultaneously. By using the short trip-contacts 45 66 instead of the continuous trip-contacts 56, a different combination of releasing the passenger supporting elements is obtainable. Some of the passenger supporting elements may be released and dropped at the left trip-contacts 66 while others may not be released and dropped until the right trip-contacts 66 are reached. The passenger supporting element 92, having its center of load forwardly of the pivot 88, the element 92 50 will swing in a forwardly direction, by gravity, to drop to the upright position. However, it is possible to overcome this action of gravity and cause the passenger supporting element 92 to drop in a rearward direction. This is accomplished by retracting the bolt 96 while the forward bolt 101 remains projected. When the bolt 96 is retracted, the engine may be quickly speeded up which will tend to pull the car frame 11 with relation to the passenger supporting element 96, and this sudden jerk will throw the inverted foot end of the supporting element 92 rearwardly and downwardly, thus dropping the supporting element 92 to the upright position. The transverse portion of the hanger 87 can trip the beveled end of the bolt 101. The solenoid winding 99 is energized when the contacts 100 55 engage the continuous trip-contacts 56 or the short trip-contacts 65, as may be desired.

It is thus seen that means are provided whereby the passenger supporting element may travel

in an inverted position with the car frame throughout the entire length of the upper run, or may be dropped forwardly or rearwardly, at any point along the upper run, or just prior to entering the upper run or prior to leaving the upper run. Various combinations of operations are therefore possible, under the complete control of the operator, rendering the apparatus interesting and producing unexpected thrills.

It is to be understood that the forms of my invention herewith shown and described are to be taken as preferred examples of the same, and that various changes in the shape, size, and arrangement of parts, may be resorted to without departing from the spirit of my invention or the scope of the subjoined claims.

Having thus described my invention, what I claim is:

1. A railway amusement apparatus, comprising a generally elliptical track including upper and lower runs of substantial length and curved ends connecting the upper and lower runs so that corresponding surfaces of the runs are inverted with relation to each other, a car, means to mount the car upon the track to travel longitudinally thereof and hold the car against turning movement with relation to the track so that the car is inverted when passing from the lower run to the upper run, a passenger supporting element pivotally mounted upon the car, means for holding the passenger upon the passenger supporting element when it is inverted, and means to cause the car and passenger supporting element to turn as a unit during the inverting movement while traveling from the lower run to the upper run upon the curved end so that the car and passenger supporting element both approach the inverted position and then to release the passenger supporting element so that it may drop to the upright position.

2. A railway amusement apparatus, comprising a generally vertical loop track including upper and lower portions having corresponding surfaces inverted with relation to each other, a car, means to mount the car upon the track to travel longitudinally thereof and hold the car against turning movement upon the track so that the car is inverted when passing from the lower to the upper portion, a passenger supporting element pivotally mounted upon the car and having means for retaining the passenger thereon when it is inverted, and means to cause the car and passenger supporting element to turn together as a unit during the inverting operation of the car and passenger supporting element and to release the passenger supporting element after it has been inverted in whole or in part so that such element may gravitate to the upright position.

3. A railway amusement apparatus, comprising a generally vertical loop track having upper and lower portions, corresponding surfaces of the upper and lower portions being inverted with relation to each other, a vehicle having a prime mover, means to mount the vehicle upon the track and to hold the same against turning movement with relation to the track so that the vehicle is inverted when passing from the lower to the upper portion of the track, a passenger supporting element pivotally carried by the vehicle and having means for retaining a passenger thereon when it is inverted, and means to hold the passenger supporting element against turning movement in one direction with relation to the vehicle and to free the same for turning movement in the opposite direction with relation

to the vehicle, the arrangement being such that the vehicle and passenger supporting element turn together during the inverting operation and the passenger supporting element may then drop to the upright position.

4. A railway amusement apparatus, comprising a generally vertical loop track having upper and lower portions, corresponding surfaces of the upper and lower portions being inverted with relation to each other, cars, means to mount the cars upon the track to travel longitudinally thereof and to hold the cars against turning movement with relation to the track so that the cars are inverted when passing from the lower portion to the upper portion of the track, a passenger supporting element pivotally mounted upon each car, each passenger supporting element having means to hold the passenger thereon when it is inverted, means to cause each car and its passenger supporting element to turn together during the inverting movement, and means to cause all of the inverted passenger supporting elements to substantially simultaneously drop to an upright position.

5. A railway amusement apparatus, comprising a generally vertical loop track having upper and lower portions, corresponding surfaces of the upper and lower portions being inverted with relation to each other, a car, means to mount the car upon the track to travel longitudinally thereof and hold the car against turning movement with relation to the track so that the car is inverted when passing from the lower portion to the upper portion of the track, a passenger supporting element pivotally mounted upon the car and having means to retain the passenger thereon when inverted, means for holding the passenger supporting element against turning movement in opposite directions with relation to the car, and means to operate the holding means to cause the same to release the passenger supporting element so that it may swing in either direction with relation to the car.

6. A railway amusement apparatus, comprising a generally vertical loop track including upper and lower portions, corresponding surfaces of the upper and lower portions being inverted with relation to each other, a car, means to mount the car upon the track and hold the same against turning movement with relation to the track so that the car is inverted when passing from the lower portion to the upper portion, a passenger supporting element pivotally mounted upon the car and having means for holding a passenger thereon when inverted, holding means mounted upon the car and engaging the passenger supporting element to prevent relative turning movement between the passenger supporting element and car during the inverting movement of the car so that the passenger supporting element is also inverted, electrical means to actuate the holding means for releasing the inverted passenger supporting element so that it may drop to an upright position, said electrical means including a contact, and a contact rail to be engaged by the contact.

7. A railway amusement apparatus, comprising a loop track including upper and lower portions having corresponding surfaces which are inverted with relation to each other, a car, means to mount the car upon the track to travel longitudinally thereof and to hold the car against turning movement with relation to the track so that the car is inverted when passing from the lower portion to the upper portion, a support

mounted upon the car and extending above the same in a generally vertical position when the car is on the lower portion of the track, a hanger pivotally mounted at its upper end upon the support and adapted to drop to an upright position when released, a passenger seat carried by the hanger to swing therewith, and a self-projecting bolt adapted to engage with the trailing side of the hanger, said bolt being adapted to be retracted by the hanger when the hanger is swung in one direction with relation to the carriage.

8. A railway amusement apparatus, comprising a loop track including upper and lower portions having corresponding surfaces inverted with relation to each other, a car, means to mount the car upon the track to travel longitudinally thereof and hold the car against turning movement with relation to the track so that the car is inverted when passing from the lower to the upper portion, a support mounted upon the car and extending above the same in an upright position when the car is arranged upon the lower portion, a generally U-shaped hanger pivotally mounted at its upper end to the support, a passenger supporting seat attached to the hanger to move therewith and having its center of gravity to one side of the pivot of the hanger, a pair of self-projecting bolts having oppositely beveled ends for movement into the path of travel of the end of the hanger, and means to retract the bolts.

9. In a railway amusement apparatus, a wheeled car, a track upon which the wheeled car travels and serving to invert the wheeled car, a passenger supporting element having means to hold the passenger thereon when it is inverted, and means to mount the passenger supporting element upon the car to cause the inverting of the car to invert the passenger supporting element and then to release the passenger supporting element so that it drops to an upright position.

10. A railway amusement apparatus to receive passengers from a loading surface, comprising an endless track disposed in a substantially vertical plane, said track having relatively long upper and lower runs and curved ends, means for supporting the track so that its lower run is arranged near the loading surface, a plurality of cars to travel upon the track and being inverted when passing from the lower run to the upper run, supports mounted upon the cars and extending inwardly from the cars to be arranged within the endless track, passenger supporting elements pivotally mounted upon the supports, the passenger supporting elements remaining within the track throughout their entire travel whereby the passenger supporting elements travel at a slower speed than the cars when the cars are traveling over the curved ends of the tracks, and means to effect the travel of the cars upon the track.

11. A railway amusement apparatus to receive passengers from a loading surface, comprising an endless track disposed in a substantially vertical plane, said track having relatively long upper and lower runs and curved ends, means for supporting the track so that the lower run is arranged adjacent to the loading surface, a plurality of cars to travel upon the track and being inverted when passing from the lower to the upper run, means to couple the cars together to provide a train to extend throughout a considerable portion of the length of the lower run, means to effect the travel of the cars upon the

track, supports mounted upon the cars and extending inwardly from the cars to be arranged within the endless track, and passenger supporting elements pivotally mounted upon the supports at points remote from the cars, the passenger supporting elements remaining within the track

throughout their entire travel whereby the passenger supporting elements travel at a slower speed than the cars when the cars are traveling over the curved ends of the track.

JOHN F. COURTNEY.
